CYLINDER FOR ELECTRIC CONTROLLERS

Aaron Slover, Clinton, Ind.

Application July 7, 1933, Serial No. 679,445

9 Claims. (Cl. 200—3)

This invention relates to controllers for electric circuits and more particularly to an improved cylinder and contact assembly for motor controllers.

5 One object of the invention is to provide an improved assembly in which portions of the contact cylinder which may become damaged by arcs caused by defective contacts or from other causes may be replaced without renewing the entire cylinder.

10 Another object of the invention is to provide a sectional cylinder which may be easily and conveniently disassembled and reassembled for the purpose of replacing damaged portions thereof and in which the various sections are securely held in proper assembled relation.

15 Another object of the invention resides in the novel structure of the sections of the cylinder whereby they are maintained in correct angular relation with respect to each other.

20 A further object of the invention is to provide a structure in which the cylinder sections are insulated from the shaft upon which they are mounted and are securely locked thereto for movement therewith.

25 A still further object of the invention is to provide improved replaceable contacts and structure for removably attaching the contacts to the cylinder sections.

30 Other objects and advantages of the invention will appear in the following description of the preferred embodiment of the invention illustrated in the attached drawings, of which

Figure 1 is an elevation of the cylinder assembly.

35 Fig. 2 is a section taken on line 2—2 of Fig. 1.

Fig. 3 is a horizontal section taken on line 3—3 of Fig. 1 showing the upper cylinder section.

40 Figs. 4, 5, 6, 7 and 8 are sectional views taken on lines 4—4, 5—5, 6—6, 7—7 and 8—8 respectively of Fig. 1 showing the central cylinder sections and their angular relation.

45 Fig. 9 is a section taken on line 9—9 of Fig. 1 showing a lower cylinder section.

Fig. 10 is a plan view of the star wheel.

45 Figs. 11, 12 and 13 are elevational views of the upper cylinder section, a central cylinder section, and a lower cylinder section respectively with the contact members removed.

50 Referring more particularly to the drawings, 1 is a shaft upon which the sectional cylinder is mounted, and 2 is a star wheel keyed to the shaft 1. An insulating bushing 3 is mounted upon the shaft 1 and serves to insulate a cylinder 4 from the shaft 1. The cylinder 4 is made up of a plurality of cylinder sections, including an upper cylinder section 5, a plurality of central cylinder sections 6 and two lower cylinder sections 7 and 7'. A large insulating washer 8 is positioned upon 60 the shaft 1 adjacent the hub of the star wheel 2

and abuts the upper end of the fiber bushing 3. A smaller insulating washer 9 is received upon the upper end of the insulating bushing 3 and is positioned between the insulating washer 8 and the upper cylinder section 5. Similarly, an insulating washer 9 is positioned upon the lower end of the insulating bushing 3, between the lower cylinder section 7', and an insulating washer 8 upon the shaft 1. The shaft 1 is provided with screw threads 10 adjacent its lower end and a nut 11 is threaded thereon against the washer 8 to secure the cylinder assembly upon the shaft between the star wheel 2 and the nut 11.

65 The shaft 1 is provided with an aperture 12 adjacent its upper end which aligns with apertures 13 in the insulating bushing and apertures 14 in the upper cylinder section 5. An insulating pin 15 extends through the aligned apertures 12, 13 and 14 to lock the contact member 5 against rotation upon the shaft. The upper cylinder 70 member 5 is provided with a projection 16 on its lower annular face which is received in a recess 17 upon the upper annular surface of the adjacent central cylinder section 6. Each of the central cylinder sections 6 is provided with recesses 17 on its upper surface and projections 16 upon its lower annular surface as is also lower cylinder section 7. The lower cylinder section 7' is also provided with a recess 17 upon its upper 75 annular surface.

80 Referring to Figs. 2 and 3, it will be noted that the upper cylinder section 5 is provided with a radial projection 18 having a radial recess 19 therein. The body portion 20 of a contact member 21 is positioned in each of the recesses 19 85 and is secured therein by means of a taper pin 22 extending through apertures 23 and 24 in the walls of the projection 18 and contact member body 20 respectively. Similarly, each of the central cylinder sections 6 is provided with a 90 radial projection 25 having a radial recess 19 in which the body portions 20 of contact members 21 are secured by a taper pin 22. The lower contact members 7 and 7' are each provided with a projecting sector 26 having three angularly 95 disposed radial recesses 19 in which are secured the body portions 20 of contact members 21 by means of taper pins 22.

100 It will be noted that the central cylinder sections 6 are duplicates, and referring to Figs. 4, 5, 6, 7 and 8, it will be further noted that the projections 16 and recesses 17 of each section 6 are angularly disposed with respect to each other. Because of the angularity between the projections 110 16 and recesses 17 upon the sections 6, the contact members 21 will be disposed in predetermined angular relation around the cylinder when the various sections 6 are assembled upon the shaft 1 and bushing 3. The recesses 17 and pro- 115

jections 16 upon the upper cylinder section 5, and the lower cylinder sections 7 and 7', are positioned with respect to the radial recesses 19 such that the contact members 21 carried thereby are positioned in predetermined angular relation with the contact members 21 upon the central cylinder section 6.

It has been found in practice that the cylinders of electric controller cylinder assemblies are frequently damaged in use, usually because of arcs caused by damage or broken contact members. The damage thus caused, is usually local in extent and in controllers heretofore known it was necessary to replace the entire cylinder. In the present device, damage to any portion of the cylinder merely requires that the nut 11 be removed from the shaft, the cylinder sections be slipped from the shaft until the damaged section is removed and a new section inserted in its place. The projections 16 and recesses 17 upon the annular faces of the cylinder sections securely lock the sections against relative angular movement, and are so disposed that it is impossible to place the sections upon the shaft in any other than the correct angular position.

While I have disclosed and described a preferred embodiment of my invention, it is understood that the structure may be varied within the scope of the following claims.

30 I claim as my invention:

1. In a cylinder assembly for electric controllers, a shaft, an insulating sleeve surrounding said shaft, a plurality of contact carrying cylinder sections surrounding said sleeve, said sections having interlocking portions to prevent relative motion therebetween and means to secure said sections to said shaft for rotation therewith, said sections being provided with radial projections having radial recesses therein, contact members having body portions received within said recesses and pins extending laterally through aligned apertures in said radial projections and body portions to lock said contact members to said sections.

45 2. In a cylinder assembly for an electric controller, a shaft, a plurality of electrically conducting contact carrying cylinder sections mounted upon said shaft and insulated therefrom and means for preventing relative rotation between said sections and said shaft, said sections being provided with radial projections having radial recesses therein, contact members having body portions received within said recesses and pins extending laterally through aligned apertures in said radial projections and body portions to lock said contact members to said sections.

60 3. In a cylinder assembly for electric controllers, a shaft, an insulating sleeve surrounding said shaft, a plurality of contact carrying cylinder sections surrounding said sleeve, said sections having interlocking portions to prevent relative motion therebetween, means to secure said sections to said shaft for rotation therewith, said means comprising a fiber pin extending through said shaft, insulating sleeve and one of said sections.

70 4. In a cylinder assembly for an electric controller, a shaft, a plurality of electrically conducting cylinder sections mounted upon said shaft in axial alignment and insulated therefrom, said sections having cooperating projections and recesses for preventing relative rota-

tion thereof and means to lock said sections upon said shaft.

5. In a cylinder assembly for an electric controller, a shaft, a plurality of electrically conducting cylinder sections mounted upon said shaft in axial alignment and insulated therefrom, said sections having cooperating projections and recesses for preventing relative rotation thereof, means to lock said sections upon said shaft, each of said sections being provided with a radial projection having a radial recess therein for receiving the body portion of an electrical contact member and a pin extending laterally of said radial recess and said body portion to lock the contact member to said section. 90

6. In a cylinder assembly for an electric controller, a shaft having a diametrical aperture extending therethrough, an insulating bushing surrounding said shaft and having apertures aligning with said aperture in said shaft, a plurality of conducting cylinder sections surrounding said insulating bushing and carrying contact members, said sections being provided with cooperating projections and recesses upon their end surfaces to prevent relative rotation therebetween, one of said sections being provided with apertures aligning with the apertures of said bushing and said shaft, a fiber pin extending through the apertures in said shaft, bushing and section to prevent relative rotation of said shaft and said sections, and means on said shaft and insulated from said sections to secure said sections against axial displacement on said shaft. 100

7. In a cylinder assembly for an electric controller, a conducting cylinder mounted upon said shaft and insulated therefrom, said cylinder comprising end annular sections and a plurality of duplicate annular central sections mounted in axial alignment, said central sections being provided with a recess upon one annular face thereof and a projection upon the opposite annular face, said projections being positioned in recesses of adjacent sections to prevent relative rotation therebetween, contact members carried by said central sections, the recess and projection of each central section being relatively angularly disposed whereby said contact members are relatively angularly disposed upon said cylinder. 110

8. In a cylinder assembly for electric controllers, a shaft, a plurality of electrically conducting cylinder sections secured coaxially of said shaft and insulated therefrom, said sections being provided with radial projections having radial recesses therein, contact members having body portions received within said recesses and pins extending laterally through aligned apertures in said radial projections and body portions to lock said contact members to said sections. 120

9. In a cylinder and contact assembly for electric controllers, a contact cylinder having a radial projection thereon, said radial projection being provided with a radial recess in its outer surface, a contact member having a body portion positioned in said recess, said projection and said body portion having aligned apertures therein, said apertures having their axis substantially perpendicular to said radial projections, and a pin positioned in said aligned apertures to secure said contact member to said contact cylinder. 140
